SPINDLE-SUPPORTING MEANS FOR
ROLLING MILLS

Ulf Geier, Osterath-Bovert, Germany, assignor to Schloemann Aktiengesellschaft, Dusseldorf, Germany

3 Claims. (Cl. 72—249)

Counterbalancing the weight of the spindles of rolling mills with rolls having their axes arranged vertically one above another is effected in a known manner by means of a rocker, one cantilever arm of which carries a journal bearing, whilst its other cantilever arm carries a counterpoise serving to counterbalance the weight of the spindle. With rolls having their axes arranged obliquely one above the other, or horizontally side by side, this known method of counterbalancing the weight is not directly applicable, since the driving spindles, when changes of roll gap occur, also execute, or exclusively execute, a slewing movement in a horizontal plane, and not, as in the case of upright roll stands, an exclusively vertical rocking movement.

The object of the present invention is to enable this known method of counterbalancing weight to be adopted in the case of horizontal roll stands also, independently of what rocking movement the spindles may execute relatively to one another upon an adjustment of the rolls occurring.

The invention consists in the feature that the rocker is made swingable about a vertical axis, and the journal bearing of the driving spindle is so arranged on one cantilever arm of the rocker as to be rockable about both a horizontal and a vertical axis. This renders it possible for the rocker to follow any change of position of the spindle, without the requisite counterbalancing of weight being thereby impaired in its action. The rocking movement of the journal bearing with two degrees of freedom is attained in a simple manner by the fact that the journal-bearing casing is supported with a vertical pivot in a stirrup supported with a pivot in the double cantilever arm of the rocker, the stirrup being rockable about a horizontal axis in the cantilever arm, and the bearing casing being rockable about a vertical axis in the stirrup.

Instead of the stirrup, rockably arranged about the horizontal on one cantilever arm or the double cantilever arm of the rocker, it is also possible to employ in an advantageous manner a bearing body with a semi-cylindrical under portion, which is so supported in a corresponding concave recess in the cantilever arm of the rocker as to be swingable about a horizontal axis. The rocker thereby admits of being made substantially narrower, since, instead of a double cantilever arm, only a single cantilever arm is required for the accommodation of the bearing body that carries the bearing casing.

Two constructional examples of the invention are illustrated in the accompanying drawings, in which:

FIGURE 1 shows a front view of the rocker, with a bearing body in the form of a stirrup for accommodating the bearing casing;

FIGURE 2 shows a side view of the rocker shown in FIGURE 1; and

FIGURE 3 a plan view of this rocker.

FIGURE 4 shows a rocker with a bearing body of a different shape for the accommodation of the bearing casing;

FIGURE 5 shows a plan of the rocker shown in FIGURE 4; and

FIGURE 6 shows a diagrammatic plan of a rolling mill

2

with the spindle-supporting means according to the invention.

In these figures, 1 denotes the base supporting the rocker. On this base a rocker block 2 is rotatably supported, by means of a pivot 3, about a vertical axis 4. Two cantilever arms 5 and 6 of the rocker, forming one member, are so supported by means of bolts 7 in the rocker block 2 as to be rockable about a horizontal axis 8.

In the constructional example according to FIGURES 1 to 3, as contrasted with the embodiment therein in FIGURES 4 and 5, the cantilever arms of the rocker are constructed as double cantilever arm 5, 5' and 6, 6' for the accommodation of a bearing body, here shown as a stirrup 9. The stirrup 9 is supported by pivots 10 and 10' in corresponding recesses 11 (FIGURE 2) in the double cantilever arm 6, 6', and is rockable about the horizontal axis 12. A journal-bearing casing 13 is axially slidable upon a spindle 14, and is so supported, with a pivot 15 in the stirrup 9, as to be capable of swinging about the vertical axis 16.

In the constructional example according to FIGURES 4 and 5, the journal-bearing casing 13 is so supported by its pivot 15 in a bearing body 17 as to be capable of slewing about a vertical axis 16. The under portion 18 of the bearing body 17 is made semi-cylindrical, and is so guided in a corresponding recess 19 in the cantilever arm 6 as to be rockable about a horizontal axis 20.

The counterpoise 21 is adjustably arranged upon the cantilever arm 5, or 5'.

Owing to the fact that the journal-bearing casing 13, in conjunction with the stirrup 9 or with the bearing body 17, is rockable relatively to the cantilever arm 6, or 6, 6' with two degrees of freedom, and, in addition to this, the rocker can also be slewed about the vertical axis, it will be gathered, particularly from FIGURE 6, that no jamming of the journal bearing for the driving spindles 14 is possible upon the adjustment of the rolls 22 lying side by side with their axes in a horizontal plane in the roll stand 23. If the rolls are adjusted afresh in the direction of the arrows 24, then the axes 25 of the driving spindles 14 assume a new position 25' in the direction of the arrows 24. In this case the rocker block 2 swings with its longitudinal axis 26 about the vertical axis 4 into the new position 26'. At the same time the bearing casing 13 turns about its vertical axis 16 in relation to the cantilever arm 6. In this new position the vertical axis of the journal-bearing casing is located at the point 16'. If the rolls are located with their axes not in a horizontal plane but in a plane inclined obliquely to the horizontal, the differences of level occurring upon the adjustment of the rolls are automatically compensated for by rotary movements of the corresponding members about the horizontal axes 8 and 12, or 8 and 20.

I claim:

1. Spindle-supporting means for rolling mills in which the rolls are not located vertically one above the other, comprising: a base, a rocker block so mounted upon the base as to be turnable about a vertical axis, a rocker so mounted upon the rocker block as to be turnable about a horizontal axis, the rocker having cantilever arms extending on opposite sides of the axis about which it turns, a counterpoise on the rocker on one side of its axis, a bearing body so mounted upon the rocker, on the other side of its axis, as to be turnable, relatively to the rocker, about a horizontal axis, and a journal-bearing casing so mounted in the bearing body that it can turn, relatively to the bearing body, about a vertical axis, the spindle to be supported being axially slidable through the journal-bearing casing, which supports it.

2. Spindle-supporting means for rolling mills as claimed in claim 1, the bearing body being formed with a convex semi-cylindrical under surface having a horizontal axis of curvature, and the rocker being formed with a concave semi-cylindrical surface in which the under surface of the bearing body rests, and about the horizontal axis of which it can turn.

3. Spindle-supporting means for rolling mills as claimed in claim 1, the bearing body being in the form of a stirrup having trunnions journaled in the rocker for its movement about a horizontal axis.
